SURGICAL BRACE

Benn A. Bunyar, Jr., Kansas City, Mo.

Application July 6, 1945, Serial No. 603,444

3 Claims. (Cl. 272—67)

1

The present invention relates to surgical braces and is particularly concerned with devices adapted for use in the treatment of the extensor and flexor muscles which control the movements of the joints of the digits of the hand.

It has been demonstrated by experience that appropriate exercises for these muscles, such as systematic opening and closing of the hand, are highly beneficial in restoring full or partial use of the digits in cases where the muscles have been impaired through accident or other cause.

The primary object of the invention is to provide a simple surgical brace which can be readily attached to the fore-arm and wrist to facilitate exercise of the muscles controlling movement of the joints of the digits, as desired.

Another object of the invention is to provide a surgical brace, for the purposes mentioned, of simpler and more compact construction than that of prior devices.

A further object of the invention is to provide mechanism which will cause no impairment of the use of the digits but, to the contrary, will facilitate the exercise called for in the treatment, whether of the digits separately or collectively and will allow the digits to be exercised successively, or two or more at the same time, or some to be flexed while the others are extended.

In its simplest and barest aspects, the invention consists of a removable brace for the fore-arm and wrist which will, to a certain extent, immobilize them without, however, impairing free use of the flexor and extensor muscles of the joints of the digits of the hand and adjustable, elastic elements carried by the brace and adapted to be attached to the digits to facilitate exercise of the said muscles.

With the foregoing objects and advantages in view, the invention consists of the novel construction and arrangement of parts hereinafter described and claimed.

Referring to the drawings,

Figure 1 is a side elevation of the surgical brace in operative position.

Figure 2 is a top plan view thereof.

Figure 3 is a transverse section on line 3—3 of Figure 1.

Figure 4 is a top plan view of the bracket that supports the fore-arm plate.

Figure 5 is a side elevation showing the elastic elements of the device rearranged for exercising the muscles of the digit joints.

Figure 6 is a bottom plan view of the device as shown in Figure 5.

2

Figure 7 is a detail view of the hand rest, being a top plan thereof.

Like numerals in the description and drawings designate the same parts of construction.

5 The brace proper comprises two rigid, parallel side bars 1, upturned at right angles at their forward extremities and there joined by two parallel, transverse bars 2 and 3 which are suitably spaced apart and provided with three vertical partitions 4, dividing the intervening space into four apertures adapted to maintain and suspend the hereinafter described elastic elements in separate relation. The side bars 1 are provided with elongated, longitudinally-disposed slots 5. Mounted 10 between said bars is a rectangular spacer-bracket 6 having two upturned branches 7 provided with vertically-disposed, parallel slots 8 suitably spaced apart and adapted to receive the threaded bolts 9 which also pass through the longitudinal slots 5 in bars 1. This construction permits vertical as well as longitudinal adjustment of the spacer-bracket and the latter is adapted to suitably space the side-bars apart and serve as a support and anchor for certain other elements of the surgical brace. Attached to the underside of said bracket is a longitudinally-disposed plate 11. It is adjustably secured thereto by means of threaded bolts passing through a longitudinal slot 12 in said plate and through the transversely-disposed slots 10 in the bottom of said bracket. The rear edge of the bracket is provided with short prongs or hooks 13 which are adapted to hold strap-ends of the elastic elements.

Between the said bracket and the suspension 35 element formed by the transverse bars 2 and 3 is mounted an inverted U-shaped element 14 adapted to hold strap-ends of the elastic elements, hooks on element 14 being provided for that purpose. The element 14 fits on the outside 40 of the bars 1 and is provided with oppositely-disposed, rectangular pins 15 projecting from the inner faces of the arms of said element and adapted to engage with rectangular, vertical notches 16 in the upper edge of bars 1, thus allowing longitudinal adjustment of element 14 to regulate the tension on the elastic elements 24. The said prongs or hooks are located on the rear edge of the top transverse part of 14.

A longitudinally-disposed, curvilinear plate 50 17 is secured to the upper surface of the transverse portion of bracket 6 and is provided with padded wrist and fore-arm straps 18 and 19 adapted to secure the said plate to the fore-arm. Attached adjustably to the top surface of plate 55 11 by threaded bolt 20a passing through a slot

is a plate 20 suitably shaped to serve as a rest for the heel and palm of the hand. Attached to the upper part of said plate is a glove-like element 21 of any suitable flexible material for the insertion of the hand when the brace is put on.

Mounted pivotally between the side bars 1 near their forward extremities is a rectangular element 22 to the underside of which is attached by strap or other suitable means a pad 23 preferably of sponge rubber and adapted to rest on the top of the fingers when the hand is in position. The pivotal connections are located at the rear, upper corners of element 22, thus permitting it to swing downward at the front when the fingers are closed, as will be seen in the arrangement of elastics shown in Figure 5.

Separate elastic strips or cords 24, of suitable retractability, are attached to the brace to exercise the fingers and another elastic strip or cord, of similar construction, is provided for the thumb. The latter elastic element is designated as 25. The elastic elements for the fingers are provided with perforated straps 26 on their rear ends to engage the hooks on the U-shaped plate 14. These finger elastics pass forwardly from plate 14, through the apertures in the upturned parts of said bars 1, where they are suspended loosely on the lower cross-bar 3, and thence to the tips of the glove-fingers. They are then doubled back along the upper surfaces of the said fingers and loosely secured thereto by loop fasteners 27. The ends of the reversed portions of these elastic elements are then secured to the top of element 22 adjacent its pivotal connection with the side bars. The elastic element 25 is secured at its forward extremity to the end of the glove thumb and at its rear extremity to the arm plate 17 near the forward end of the latter. An elastic strap or cord 28 is attached to the upper, forward corner of element 22 and is provided on its rear end with a perforated strap attachment adapted to hook on the rear edge of bracket 6. The elastic cord 28 is adapted to impart a downward pull on the finger-pad element 22 and to aid in the finger exercises by providing a counteracting force against the action of the extensor muscles.

In operation, the hand is inserted in the glove-like element and the surgical brace is strapped on the fore-arm and wrist. If the flexor muscles are to be exercised the fingers and thumb are bent as much and as often as prescribed. The elastic elements 24 and 25 produce a counteracting force against which the flexor muscles work, or if the extensor muscles are to be treated the elastic elements 24 are removed from element 14 and suspension member 3 and the free ends thereof are passed under the surgical brace to the underside of the bracket 6 where their strap attachments are hooked to the projections thereon. It will be understood that the elastic elements for all digits will have suitable retractability to produce the counterforce hereinbefore mentioned. In the treatment of the flexor and extensor muscles, the character and frequency of the exercises will be as prescribed by the medical practitioner. These surgical braces can be made for right or left hand or the same brace can be used for both hands with obvious rearrangement. While in the embodiment of the invention here shown, it is adapted to the left hand, the brace can be changed for use on the right hand by substituting a right-hand glove and reversing the hand rest 20.

Having thus described my invention, what I claim as new and desire to secure by Letters Patent is:

1. A surgical brace for treatment of the flexor and extensor muscles of the digits of the hand comprising rigid, longitudinally-disposed, parallel side bars provided at their forward extremities with transverse, upturned portions adapted to serve as a suspension bridge to maintain the retractile elements for the finger digits in separate relation, a curvilinear plate adjustably mounted between said side bars and adapted to retain the fore-arm, wrist and hand in proper position, a hand rest connected with said fore-arm plate, retractile elements for the fingers adapted to be suspended on said transverse member of the frame and removably attached to the fingers, the rear ends of said retractile elements being attached to the frame, a retractile element attached at one end to the curvilinear plate and removably attachable at the other end to the thumb, an arched member mounted on said frame and provided with means for attachment of the forward ends of the retractile elements for the fingers, means for regulating the tension on same comprising a plurality of vertical, rectangular slots in the upper edges of the said bars of the frame, rectangular pins projecting from the inner vertical surfaces of said arched member and adapted to seat in oppositely-disposed vertical slots in said bars, and means for adjusting the fore-arm plate in relation to the side bars of the frame.

2. A surgical brace for treatment of the flexor and extensor muscles of the digits of the hand comprising rigid, longitudinally-disposed, parallel side bars provided at their forward extremities with transverse, upturned portions adapted to serve as a suspension bridge to maintain the retractile elements for the finger digits in separate relation, a transversely-disposed bracket adjustably connected to said side bars, a longitudinally-disposed plate provided with an elongated slot and attached for transverse adjustment to the underside of the bracket by threaded bolts passing through said elongated slot in said plate and transverse slots in the bottom part of said bracket, a curvilinear plate attached to the upper surface of the bracket bottom and adapted to retain the fore-arm, wrist and hand in proper position, a plate adjustably secured to the forward end of said longitudinal plate and adapted to serve as a hand rest, a glove-like element attached to said hand rest, retractile elements for the fingers adapted to be suspended on said transverse member of the frame and removably attachable to the fingers, the rear ends of said retractile elements being attached to the frame, a retractile element attached at one end to the curvilinear plate and removably attachable at the other end to the thumb, an arched member mounted on said frame and provided with means for attachment of the forward ends of the retractile elements for the fingers, means for regulating the tension on same comprising a plurality of vertical, rectangular slots in the upper edges of the said bars of the frame, rectangular pins projecting from the inner vertical surfaces of said arched member and adapted to seat in oppositely-disposed vertical slots in said bars, and means for adjusting the fore-arm plate in relation to the side bars of the frame.

3. The device defined in claim 2 and a pad 75 pivotally connected to said frame and adapted

to bear on the top of the fingers during treatment of said muscles.
